ELECTRICAL SIGNALING SYSTEM

Filed Sept. 13, 1937

UNITED STATES PATENT OFFICE

2,194,063

ELECTRICAL SIGNALING SYSTEM

Charles Edmund Beale, Liverpool, England, assignor to Associated Telephone & Telegraph Company, Chicago, Ill., a corporation of Delaware

Application September 13, 1937, Serial No. 163,596
In Great Britain October 17, 1936

17 Claims. (Cl. 179—16)

The present invention relates to electrical signaling arrangements and is more particularly concerned with an improved method of signaling in response to the momentary reduction of an otherwise steady current flow in the signaling circuit. It has already been suggested in an arrangement of this character to employ as a responding device a relay specially constructed to have a very short release time so that it will respond to current changes of extremely small duration. The chief object of the invention is to obtain the same facilities by a suitable circuit arrangement of relays of the type ordinarily employed which are cheap to manufacture and do not require a critical adjustment to enable them to perform their functions satisfactorily.

According to the invention in an electrical signaling arrangement for effecting a switching operation in response to a signaling operation comprising the momentary opening of the signaling circuit and its subsequent completion by way of an impedance, a relay initially energised in a local circuit is maintained energised over the signaling circuit, the relay being wound and the spring tension adjusted so that reliable de-energisation will take place in response to a signaling operation of very short duration.

The invention is advantageously employed in telephone or like switching systems where it is desired to give an indication of the extension of a highly inductive circuit in which the electrical conditions after extension are not substantially changed but in which a momentary interruption of the current flowing in this circuit occurs during the act of extension. The invention finds one useful application in the case of a telephone system employing register senders. By signaling to the register sender the instant at which a switch which has performed a hunting operation switches through to a succeeding switch, it is possible to arrange for the pause between successive trains of impulses transmitted by the register sender to be reduced to just the amount required and thus the operation of the system is speeded up.

Referring now to the accompanying drawing this shows sufficient of the circuits of a register sender of the type disclosed in British Patent No. 469,184 granted July 20, 1937 to Reginald Taylor and George Thomas Baker to enable the invention to be fully understood. The circuits are limited for the most part to an impulse sending arrangement which is substantially unchanged from that of the before-mentioned patent except for the addition of relays P, Q and R. Shown schematically is the register K which in the well

known manner receives digits, stores them, and then in accordance with the value of the digits controls the transmission of trains of impulses by the impulse sender. The drawing also shows a train of switches X, Y and Z of the two motion type. Such switches are completely disclosed in Patent No. 1,368,994 granted July 26, 1932 to Norman H. Saunders, and the present showing of them therefore includes only so much of the switches as is necessary to understand the invention.

The manner in which switches X, Y and Z function, while not new, will be reviewed briefly before explaining the operation of the impulse sender. When the impulsing loop circuit from the sender is completed to switch X (in any known way, this not being a part of the present invention) line relay A in the switch is energized over: earth, battery, the upper winding of relay A, contact h^1 , the negative side of the line, wiper S2 in position 1, the positive side of the line, contact h^2 , the lower winding of relay A and earth. Relay A operates and energizes relay B in an obvious circuit extending over contact a^1 ; relay B operating prepares a testing circuit to wiper P. As will be described presently relay A is then operated impulsively over the line and in the known way controls the stepping of the wipers of switch X to some level of its contact bank after which they are automatically rotated in search for an idle line in that level. During the impulsive operation of relay A, relay B remains operated by virtue of being slugged or otherwise made slow to release. When the wipers find an idle line, for example that leading to switch Y, relay H operates over: earth, contact b^1 , the right hand winding of relay H, contact b^2 , wiper P, contact l^b^1 , resistance W^b^1 , battery and earth. Relay H halts the hunting movement of the switch wipers and switches over contacts h^1 and h^2 , thereby extending the impulsing loop to line relay l^A in switch Y which immediately energizes thereover. Relay l^A upon operating closes contact l^a^1 to energize relay l^B . By the closure of contacts h^3 and h^4 upon operation of relay H, and the switching over of contact l^b^1 upon operation of relay l^B , relay H is locked up over: earth, battery, the left hand winding of relay H, contact h^3 , the right hand winding of relay H, contact h^4 , wiper P, contact l^b^1 and earth. Therefore when line relay A in switch X releases upon the switching over of contacts h^1 and h^2 and thereby promotes the delayed release of relay B by opening contact a^1 , relay H does not release despite the opening of its original energizing circuit at contacts b^1

- and b_2 . Relay $1A$ is then operated impulsively over the line in the same manner as was relay A to cause the wipers of switch Y to search for an idle line in some desired level of its contact bank, 5 and when one is found, for example the line leading to switch Z , relay $1H$ energizes over: earth, contact $1h_1$, the right hand winding of relay $1H$, contact $1b_2$, wiper P , contact $2b_1$, resistance W_2 , battery and earth. Relay $1H$ switches the line 10 through to relay $2A$ of switch Z by operation of contacts $1h_1$ and $1h_2$, and closes a locking circuit for itself at contacts $1h_3$ and $1h_4$, which locking circuit is completed at contact $2b_1$ when relay $2B$ operates over contact $2a_1$ responsive to the 15 energization of relay $2A$ over the line loop. While in the drawing switch Z is the last switch to which the line loop is extended, i. e. a connector, it will be appreciated that without departing from the spirit of the invention there may be more 20 than two selector switches such as X and Y through which the line is extended before reaching the connector. Also the invention is not intended to be limited to the specific circuit details of selectors X and Y which are shown, these having been chosen merely to illustrate the manner in which switches of this type "switch through" each thereby disconnecting its own line relay and almost simultaneously connecting up the line relay of a succeeding switch. 25
- 30 The general impulse sending arrangements of the known scheme will now be described briefly. When sufficient digits have been received by the register (shown schematically as K in the drawing) for the destination of the call to be known, a start circuit is completed for the impulse sender by closure of contact st . In the sender, impulse springs IMP_1 and IMP_2 are continuously operated at a speed of ten impulses per second, and springs IMP_2 periodically short-circuit relay IG ; 35 consequently relay IG operates over: earth, start contact st in the register, contact $s2_4$, relay IG , resistance YN , battery and earth, only when the impulse springs IMP_2 next open and remove the short-circuit. These springs are then connected 40 to the magnet SM of the sender switch S by the switching over of contact ig_1 , and this switch is stepped round at a speed of ten impulses a second over the following circuit: earth, contacts st , $s2_4$, IMP_2 and ig_1 , magnet SM , battery and earth. 45
- 45 When the sender switch reaches position 3, the short-circuit around impulse springs IMP_1 which previously extended over wiper S_2 and contact $s2_2$ is removed, and the outgoing loop circuit is completed from the negative lead, over impulse springs IMP_1 , contact $s2_2$ and wiper S_2 to the positive lead; this circuit is interrupted periodically by impulse springs IMP_1 thereby to 50 transmit a train of impulses to the first selector X while impulse senders IMP_2 continue to step the sender switch. The springs IMP_1 and IMP_2 it should be mentioned operate 180° out of phase with one another. After the required number of 55 impulses in the first train have been transmitted, relay SZ is operated by a marking placed upon bank S_4 of the sender switch by register K , and this relay thereupon locks up to the sender switch homing bank S_3 by closing contact $s2_3$. It also at armature $s2_2$ short-circuits the springs IMP_1 to prevent the transmission of further impulses, at 60 armature $s2_4$ releases relay IG and at armature $s2_5$ prepares a homing circuit for the sender switch. By the closing of contact ig_3 upon release of relay IG the circuit: earth, wiper S_1 , contact ig_3 , interrupter contact sm of the magnet SM , magnet SM , battery and earth, is completed 65

for advancing the sender switch by self-interruption until it reaches contact 15 whereupon relay IG is again operated over the circuit: earth, wiper S_1 in position 15 , contacts $s2_5$, q_2 , relay IG , resistance YN , battery and earth. The self-interrupted circuit for the magnet SM is thereupon opened by contact ig_3 , and the sender switch is then advanced to contact 19 by impulses from the springs IMP_2 over the circuit: earth, wiper S_1 of the sender switch, contacts $s2_5$, q_2 , IMP_2 and ig_1 , magnet SM , battery and earth. Thereafter the sender switch is again advanced by self-interruption over: earth, wiper S_1 , contacts ig_3 and sm , magnet SM , battery and earth, and when it reaches its home position relay SZ is released and the sending of the second series of impulses is initiated. The length of the interdigital pause is therefore determined primarily by the time taken for the sender switch to step over contacts $15-18$ under the control of the springs IMP_2 . 20

With the modified circuits according to the invention however, when relay SZ operates to terminate the impulse train a circuit is completed over contacts $s2_1$ and r_2 for the lower winding of relay P and also the upper winding is inserted in the outgoing loop by the switching over of contact $s2_2$. Relay P is operated over its lower winding and at armature p_2 energises relay R over: earth, contacts $s2_1$ and p_2 . Relay R , by switching over armature r_2 locks up independent of contact p_2 , and disconnects the lower winding of relay P . Relay P is so adjusted that when it is once energised it will just hold operated by current flow through its upper winding over the outgoing loop, this winding being somewhat inefficient. 30

When the first selector completes its hunting operation and switches through, the loop is momentarily opened by the operation of relay H and there is thus a momentary interruption in the current flow through relay P . Moreover, when armatures h_1 and h_2 engage their front contacts the inductance of the de-energised line relay $1A$ delays the rise of the loop current to its normal value. This reduction in the current through relay P is sufficient to cause its de-energisation. At armature p_1 the upper winding of relay P is short-circuited over contact r_1 to prevent its re-operation when the loop current is restored, while at armature p_2 a circuit is completed over: earth, contacts $s2_1$, p_2 and r_3 , to operate relay Q . This relay locks up at armature q_1 and at armature q_2 alters the stepping circuit for the sender switch magnet SM so that the switch is advanced over contacts $15-18$ not under control of the impulse springs IMP_2 as in the known scheme, but by self-interruption over the circuit: earth, wiper S_1 , contacts $s2_5$ and q_2 , interrupter contact sm , magnet SM , battery and earth. Consequently the sender switch is advanced to its home position more rapidly and on the release of relay SZ relays Q and R are released by the opening of contact $s2_1$; therefore the sending of the succeeding series of impulses is initiated after only the length of pause actually required rather than after a pause whose length is arbitrarily fixed to a predetermined minimum by the comparatively slow stepping of the sending switch over contacts $15-18$ under control of springs IMP_2 . 55

It will be appreciated that as an alternative to the arrangement for short-circuiting relay P upon its release as shown, the re-operation of relay P could be prevented by connecting it in the outgoing loop circuit over its own operated contact r_3 . 70

tacts. Since the last switch of the train will ordinarily be the connector which responds to two digits, there will be no momentary signal sent back after the transmission of the penultimate digit and consequently in this case the register sender will give the full inter-digital pause since relay P will remain operated. Relay P is, of course, de-energised by the short-circuiting effect of armature S22 when relay SZ falls away. Similar considerations apply to the case where the call is extended to another exchange over a repeater though comparatively small changes would be necessary to enable the repeater to relay back the momentary signal.

15 It will be understood that the register sender may be provided in the usual manner with a polarised relay to hold up the sending beyond the normal interdigital pause in case a double or extended hunting operation is required between two successive switching stages.

I claim:

1. In a switching system, wherein the extension of a connection over an automatic switch may be controlled by transmitting impulses over a circuit extending to said switch, and wherein the extension of said connection is effective to transitorily interrupt said circuit, a relay in said circuit, and means for rendering said relay ineffective during said impulsion and for thereafter rendering said relay responsive to said transitory interruption of said circuit to indicate that said connection has been extended.

2. In a switching system, wherein an automatic switch having a control circuit extending thereto is adapted to signal revertively over said circuit responsive to the extension of a connection by said switch, means for signalling over said circuit to said switch thereby to control same to extend the connection, a relay, means for placing said relay under the control of said circuit upon completion of said last signalling, said relay thereafter responding to the signalling over said circuit by said switch to indicate when said connection is extended.

3. In a switching system, wherein connections are extended progressively over a plurality of automatic switches, a control circuit, means for controlling each switch in turn over said circuit to extend said circuit to a succeeding one of said switches, a relay in said circuit, and means for rendering said relay inoperative during the controlling of a switch and for thereafter rendering it responsive to the extension of said circuit from that switch to the succeeding switch.

4. In a switching system, a circuit extending to an automatic switch, a relay included in said circuit, another circuit for said relay, means for initially operating said relay in said other circuit and for holding it operated in said first circuit, and means in said switch for extending said first circuit through said switch, said relay responsive to said extension of said circuit through said switch to indicate that said circuit has been so extended.

5. In a switching system as claimed in claim 4, an impulse sender controlled by said relay to start transmitting impulses over said first circuit substantially immediately after the extension thereof through said switch.

6. In a switching system, a control circuit extending to an automatic switch, means for variably controlling said switch over said circuit to cause same to extend a connection, a relay, a first circuit for said relay including said controlling circuit, a second circuit for said relay,

and means for initially operating said relay over said second circuit and for holding it operated over said control circuit, said relay thereafter responsive to the extension of said connection.

7. In a switching system, a control circuit extending to an automatic switch, means for transmitting impulses over said control circuit to cause said switch to extend a connection, a relay in said circuit, said relay inoperative during said impulsion, another circuit for said relay, and means for transitorily energizing said relay in said other circuit after said impulsion has been completed to operate said relay and for causing it to be held operated over said control circuit, said relay thereafter responsive to the extension of said connection. 5

8. In a switching system, wherein connections are extended progressively over a plurality of automatic switches, a control circuit, means for transmitting impulses over said control circuit to each of said switches in turn to cause that switch to extend said control circuit to a succeeding switch, a relay in said control circuit, a second circuit for said relay, means for initially operating said relay in said second circuit upon the termination of said transmission of impulses to a switch and for holding it operated in said control circuit, said relay thereafter responsive to the extension of said control circuit to the succeeding switch. 20

9. In a switching system, a control circuit, a sender for transmitting trains of impulses over said control circuit, a relay in said circuit, another circuit for said relay, means effective upon termination of the transmission of a train of impulses to initially operate said relay in said other circuit and to thereafter hold said relay operated in said control circuit, and means for transitorily interrupting said circuit to release said relay, said relay effective upon its release to control said sender to initiate the transmission of the next train of impulses. 30

10. In a switching system, a control circuit, a sender for transmitting trains of impulses over said circuit to control automatic switches one after another to progressively extend said circuit, a relay, and means effective upon termination of the transmission of a train of impulses to a switch for placing said relay under control of said circuit, said relay thereafter responsive to the extension of said circuit from that switch to a succeeding one of said switches to thereby cause said sender to begin to transmit the next train of impulses to said succeeding switch substantially at once. 45

11. A switching system as claimed in claim 10, wherein said sender includes means for introducing, between successive trains of impulses transmitted over said circuit, a pause lasting a predetermined minimum length of time, and wherein said relay, responsive to the extension of said circuit through a switch before the expiry of said minimum length of time, renders said last means ineffective thereby to substantially eliminate the remainder of said pause. 60

12. In a switching system, a control circuit, a sender for transmitting trains of impulses over said circuit to control automatic switches one after another to progressively extend said circuit, means in said sender for introducing a pause between successive impulse trains, a relay in said circuit, another circuit for said relay, and means effective upon termination of the transmission of a train of impulses to each switch for initially operating said relay in said other circuit and for 70

- holding it operated in said control circuit, the extension of said control circuit from that switch to a successive switch during a portion of said pause following said impulsive effective to release said relay to thereby cause the remainder of said pause to be substantially eliminated.
13. In a switching system, a control circuit, means for transmitting trains of impulses over said circuit to direct the progressive extension of 10 a connection through automatic switches, a relay, a first circuit for said relay including said control circuit, means for rendering said first circuit ineffective during the transmission of a train of impulses to a switch, a second circuit for said relay, means for rendering said first and said second circuits effective, upon completion of said transmission of said train of impulses to said switch, to operate said relay, means for interrupting said second circuit and for thereafter holding 15 said relay operated in said first circuit, the extension of said connection from said switch to a successive switch effective to transitorily interrupt said control circuit and thereby release said relay, and means effective upon release of said relay for rendering said first circuit ineffective until transmission of the next train of impulses is initiated.
14. In a switching system having a pair of current feeding bridges of substantially the same potential, a circuit connected to one of the bridges, change-over means for disconnecting said circuit from said one bridge and for at once connecting it to the other bridge, said bridges being so poled that current flows over said circuit in 20 the same direction both before and after the operation of said change-over means, inductance included in said other bridge to delay the growth of current supplied thereby to said circuit, whereby there is a transitory reduction in the value of 25 the current flow over said circuit upon operation of said change-over means, and a relay connected in said circuit and actuated by said transitory reduction in the flow of current.
15. In a switching system having a pair of current feeding bridges of substantially the same potential, a relay, means for initially operating said relay, a circuit for said relay thereafter effective to maintain same operated from current supplied by one of said bridges, change-over means for disconnecting said one bridge from said circuit and for substantially simultaneously connecting thereto the other of said bridges, said other bridge being poled in the same direction as 10 said first bridge but containing inductance to delay the growth of the current supplied to said circuit by said other bridge, whereby said relay is released by the transitory reduction in the value of current flow in said circuit responsive 15 to the operation of said change-over means.
16. In a switching system as claimed in claim 15, means including a contact on said relay for short-circuiting said relay upon its release thereby to prevent reoperation of same following said 20 transitory reduction in the value of current-flow in said circuit.
17. In a switching system having a pair of similar current feeding bridges, a circuit connected to one of said bridges, change-over means for disconnecting said circuit from said one bridge and for at once connecting it to the other bridge, said bridges being so poled that current flows over said circuit in the same direction both before and after the operation of said change-over means, a 30 relay operated over said circuit responsive to the transitory interruption of current in said circuit upon operation of said change-over means, an impulse sender rendered effective by the operation of said relay thereupon to interrupt said 35 circuit one or more times in succession, and means for rendering said relay non-responsive to the interruption of said circuit by said impulse sender.

CHARLES EDMUND BEALE. 40
